UNITED STATES PATENT OFFICE.

ANTON DVORAK, OF BERWYN, ILLINOIS, ASSIGNOR TO BEARDSLEE CHANDELIER MANUFACTURING COMPANY, OF CHICAGO, ILLINOIS, A CORPORATION OF DELAWARE.

LIGHTING FIXTURE.

Application filed May 26, 1924. Serial No. 715,845.

My invention relates more particularly to a supporting member or loop whereby the glass holding shell and the lamp holding socket member are held in place and the assembled elements suspended from the supporting chain or rod of the fixture.

My invention has for its object the provision of a construction whereby the porcelain receptacle or lamp holding socket with the glass holding shell will be properly secured in place and suspended at various points from the supporting rod or chain which secures the fixture to the wall bracket or ceiling plate; a construction whereby all possibility of the lamp holding socket member becoming loosened when the bulb is being screwed out of the socket will be prevented; and a two point suspension for the lamp bulbs and shades provided and a more easy balance of the fixture obtained.

The above enumerated objects and the advantages inherent in the invention will all be more readily comprehended from the detailed description of the accompanying drawing, wherein:

Figure 1 is an elevation of a portion of a lighting fixture with my invention.

Figure 2 is an enlarged sectional view of my improved means and the glass holding shell and lamp holding socket member with portions broken away.

My invention consists more particularly in the loop or supporting member shown at 10 which consists of the body or loop portion 11 adapted to receive the ring or link of a chain as indicated at 12; or other suitable suspending member whereby the fixture is suspended from the wall bracket or from the ceiling. The member also consists of the main somewhat elongated base portion 13 which is preferably substantially flat throughout the major portion of the lower surface and apertured centrally at 14 for the passage of the electric wires 15. The base portion 13 is shown as preferably extending slightly beyond the sides of the loop portion 11; and each of the extended portions or arms 16, 16 is provided with a tapped opening on the lower side or bottom to receive a screw 17. The bottom surface of the base portion 13 is preferably provided with a boss 18 disposed about the opening 14, adapted to pass through a central opening in the shade holding shell 19 which assists in the proper positioning or assembly of the

various elements; and this boss also acts as a bushing through the thin walls of the shell 19 and prevents cutting of the insulation on the wires. The shade holding shell 19 may be of the usual and well known construction 60 employed, with the skirt portion thereof provided with any suitable fastening means, as for example the thumb-screws 20 whereby the glassware 21 is removably secured in place.

The screws 17 are of length sufficient to not only pass through the top of the shell 19 and into the tapped openings in the bottom of the member 10, but these screws are also intended to secure the porcelain socket 70 member 22 in place. With my invention, the porcelain member 22 may be of the type more generally known as a receptacle which is provided with a central opening for the free passage of the electric wires 15, as 75 shown in Figure 2; and adapted to receive the bulb 23 in the usual manner. As shown in Figure 2, the porcelain member 22 is cut away or undercut at the sides as shown at 24, with the base portion at these points 80 apertured for the passage of the screws, the undercut portions 24 enabling the screws to be put into place and screwed into the tapped openings in the lower side of loop member 10, thereby causing the porcelain 85 member to firmly clamp the shell 19 against the under side of loop member 10.

My invention, aside from providing a two point suspension for the glass holding shell 19—which is of great importance especially 90 where large bowls or shades are employed—enables the fixture to be more readily balanced. With the suspending means providing a multiple of attaching points, namely a two-point suspension in the particular 95 exemplification, the difficulty heretofore encountered with suspended fixture of the type in question due to the backing off or unscrewing of the socket member, either through vibration or repeated removals and 100 replacements of the bulb, is entirely eliminated.

In fixtures as heretofore employed, the supporting member was usually provided with an externally threaded nipple, arranged centrally for the passage of the electric wires. 105 The bulb or lamp holding socket member was provided with a threaded socket to permit the socket member to screw onto the threaded nipple of the supporting member of the fixture, with the shell held between the 110

socket member and the supporting member, so that the shell with the attached bowl or shade, as well as the lamp or bulb in the socket member were all merely supported 5 through the single connection between the supporting member and the socket member, namely by means of the socket member screwing onto the threaded nipple. In practice, with fixtures of this type, it has been 10 found, either through vibration or through the unscrewing and replacement of the bulbs, that the bulb holding receptacle is frequently caused to back off or unscrew from the threaded nipple and as a result the wires 15 are frequently twisted and broken, or in the insulation on the wires damaged so as to result in a short circuit; while at the same time often allowing the socket and bulb, together with the bowl or shade, to fall and 20 become damaged and broken.

With my improved construction, the difficulty and danger above referred to are entirely eliminated and prevented, as the unscrewing of the bulb from the socket member 25 can in no way disturb the fastening elements nor in any way affect the secure relation between the receptacle or bulb holding member, the glassware holding shell and the supporting member or loop. Furthermore, 30 with my invention, the shade holding shell, which usually is of comparatively thin sheet metal, rests on the entire base of the receptacle, thus receiving support substantially throughout the top of the shell instead of 35 merely at the central opening as is the case with constructions as heretofore employed and hereinbefore referred to. At the same time, my invention permits an easy balance

of the fixture to be obtained; the invention being of simple construction and one which 40 may be easily and quickly put into place; and I have described the invention in terms which are employed merely as terms of description and not as terms of limitation, as structural modifications are possible and 45 may be made without, however, departing from the spirit of my invention.

What I claim is:

In a lighting fixture, a supporting member provided at top with a loop portion to receive a suspending element, the base of the member being centrally provided with an apertured boss on the lower face for the passage of electric wires, said base being extended on opposite sides of the central opening with a flat bottom face having a tapped opening at each end, a lamp holding socket member having an apertured laterally disposed upper portion, a shade or bowl-holding shell centrally apertured at top to receive said apertured boss and provided with openings on opposite sides registering with the tapped openings in the base of the supporting member, the top of said shell being clamped between the supporting member and said socket member, and fastening means disposed through the lateral portion of the socket member, the openings in said shell and the tapped openings in the bottom of the extended portion of said supporting member, whereby a plurality of independent suspension points on opposite sides of the median line of the supporting member are provided.

ANTON DVORAK.
